CIRCUMCISING INSTRUMENT

Abraham Z. Krohn, Brooklyn, N. Y.

Application September 10, 1952, Serial No. 21,402

Term of patent 14 years

(Cl. D83—1)

To all whom it may concern:

Be it known that I, Abraham Z. Krohn, a citizen of the United States of America and a resident of Brooklyn, county of Kings, and State of New York, have invented a new, original, and ornamental Design for a Circumcising Instrument, of which the following is a specification, reference being had to the accompanying drawing, forming a part hereof, wherein:

Fig. 1 is a side elevational view of a circumcising instrument, embodying my new design;

Fig. 2 is a top plan view thereof; and

Fig. 3 is a bottom plan view of the instrument.

I claim:

The ornamental design for a circumcising instrument, substantially as shown.

ABRAHAM Z. KROHN.
